SWITCH OPERATING MECHANISM

Thomas M. Cole, New York, N. Y., assignor to
 Federal Electric Products Company, Inc., Newark, N. J., a corporation of New Jersey

Application May 7, 1943, Serial No. 486,001

20 Claims. (Cl. 200—18)

This invention relates to double-throw electric switches and more particularly to a switch operating mechanism for a double-throw electric switch.

The primary object of the invention is to provide an improved quick-make and quick-break switch-operating mechanism for a double-throw switch in which the movable contact member is movable to a neutral or open circuit position.

This object of the invention and other objects ancillary thereto will best be understood from the following description with reference to the accompanying illustrative drawings.

In the drawings:

Fig. 1 is a front view, in elevation, of a switch provided with switch operating mechanism embodying the present invention, parts of the casing being broken away for the purpose of illustration;

Fig. 2 is a side view of the switch;

Fig. 3 is a sectional view on the line 3—3 of Fig. 1;

Fig. 4 is an exploded perspective view of certain parts of the operating mechanism and a portion of the switch casing;

Fig. 5 is a fragmentary sectional view, on a larger scale on the line 5—5 of Fig. 2;

Fig. 6 is a sectional view on the line 6—6 of Fig. 1;

Fig. 7 is a sectional view on the line 7—7 of Fig. 1, showing the neutral position of the switch operating mechanism;

Figs. 8 and 9 are views similar to Fig. 7 showing the positions of the operating mechanism when the movable contact member of the switch is in the two different closed positions thereof, respectively.

Fig. 10 is a view taken on the line 10—10 of Fig. 7, the spring of the spring projected rod being omitted;

Fig. 11 is a side edge view of a part of the mechanism.

Referring now to the drawings in detail, the double-throw switch 10 provided with a switch operating mechanism embodying the present invention comprises, as here shown, a casing 12 provided with a hinged cover 14 held in closed position by the releasable latches 16. The switch unit 18 which is mounted within casing 12 comprises an insulation base 20 secured to the casing wall 22 in any suitable way as by screws 24. As the switch, as illustrated, is a double-throw switch and has two poles, said switch comprises stationary contact members 26 and stationary contact members 28 provided with terminal mem-

bers here shown as fuse clips 30 and 32, said stationary contact members and fuse clips being secured to insulation base 20. The line terminals also here shown as fuse clips 34 and 36 are secured to base 20 for receiving the ends of the fuses (not shown), the opposite ends of which are received in fuse clips 30 and 32, respectively, of the two poles. Terminal members 38 and 40 are secured to fuse clips 34 and 36, respectively, in electrical connection therewith. A movable contact member 42, for each pole, is pivotally secured to a metal lug 44 (Fig. 6) by a pivot pin 46 for oscillatory movement of said movable contact member to and from a neutral position for engagement with and disengagement from said stationary contact members. More particularly, as here shown, each movable contact member 42 comprises two blades 48 and 50, in integral relation, for engagement with the companion stationary contact members 26 and 28, respectively. In Fig. 6, the movable contact member is shown in full lines in its neutral position, and in dotted lines in engagement with the contact member 28. Lug 44 is secured to base 20 and is provided with a terminal 52 for the connection thereto of the incoming end of the line. As shown, the stationary contact members 26 and 28 are positioned in companion arcing chutes 54.

The movable contact members 42 are actuated by a crank member 56 which forms a part of the switch operating mechanism as hereinafter more fully described. Said crank member 56 comprises the crank portion 58, the aligned pivot portions 60 and 62 and the crank arms 64 and 66. The movable contact members 42 are operatively connected to crank portion 58 of crank member 56 by companion insulation members 68 secured to the blades 48 and 50 of the companion movable contact member and provided with a recessed portion 70 which engages the grooved insulation collars 72 mounted on crank portion 58 of crank member 56. While the switch unit as hereinbefore described is preferred and is illustrated in order to show a complete switch, it will be understood that the switch operating mechanism of the present invention is not limited in its application to a double-throw switch unit of this particular construction, but may be used with other switch units.

The switch operating mechanism for operating the switch through the crank member 56 will now be described:

The aligned pivot portions 60 and 62 of crank member 56 are journalled for pivotal movement

in the casing wall 74 and in the bearing or mounting member 76, respectively, (Figs. 3 and 6). Said bearing member 76 comprises a part 78 which is provided with a cylindrical recess 80, in which end portion 62 of said crank is journaled for oscillation, and an integral stem 82 having a smooth cylindrical portion 84 and a screw threaded portion 86. Said stem projects through a circular opening 88 in the adjacent casing wall 90. Members 92, 94 and 96 (Fig. 4) are mounted for pivotal movement on stem portion 84 and as more clearly shown in Fig. 5 are positioned between the inner surface of casing wall 90 and the confronting surface 98 of part 78 of mounting member 76, said members 92, 94 and 96 being provided with bearing openings 100, 102 and 104, respectively. A control member 106, here shown as an operating handle, has a flat hub portion 108 which is mounted for turning movement on cylindrical portion 84 of stem 82, being provided for that purpose with a bearing opening 110. Control member 106 is positioned externally of the casing with the hub portion 108 thereof abutting the outer surface of casing wall 90, with a washer (not shown) interposed therebetween if so desired. Nuts 112 and 114 are threaded on portion 86 of stem 82 and hold members 92, 94, 96 and 106 in fixed relation axially of mounting member 76 and holds said mounting member against movement axially of opening 88 of casing wall 90 without, however, interfering with the pivotal movement of members 92, 94, 96 and 106.

The construction and inter-relationship of members 92, 94, 96 and 106 will now be further described. Member 92 has an axial lug 116 which extends into the recesses 118 and 120 of members 94 and 96, respectively. The circumferential extent of each of said recesses is greater than lug 116. Said member 92 is also provided with circumferentially spaced axial lugs 122 and 124 located at opposite sides, respectively, of crank arm 66 of crank member 56, in position to engage the latter at opposite sides thereof. In the neutral position of the crank member 56, said lugs are spaced from crank arm 58 thus providing a lost motion connection between member 92 and crank member 56. In the neutral position of the switch, crank member 56 is centered between lugs 122 and 124 by tension springs 125 which are secured to casing wall 74 and to member 127 which engages crank arm 64 of said crank member. Member 94 is provided with a lug 126 which projects through an arcuate slot 128 in member 96, through an arcuate slot 130 in casing wall 90, and through an arcuate slot 132 in the hub portion 108 of control member 106, said lug 126 being movable circumferentially of said slots. Member 96 has an axial lug 134 which projects through the arcuate slot 130 in casing wall 90 and through an arcuate slot 136 in the hub portion 108 in control member 106, said lug 134 being movable circumferentially of said slots.

It will be observed that the arcuate slots 132 and 136 of control member 106 are circumferentially spaced from each other (Figs. 2 and 4) and that the circumferential extent of each of said slots is greater than the circumferential extent of the companion lugs 126 and 134, respectively, thus providing a lost motion connection between said control member and each of said members 94 and 96. Members 94 and 96 are provided with radial ears 138 and 140, respectively, which are axially offset from the face of said members, respectively, by the integral axial

portions 142 and 144, respectively. As illustrated in Fig. 7, which shows the neutral position of the operating mechanism when the movable contact member is in its neutral position out of contact with both stationary contact members 26 and 28, portions 142 and 144 of members 94 and 96, respectively, engage or are engaged by the adjacent side edges 146 and 148, respectively, of radial portion 150 of member 92. A spring projected rod 152 is pivotally connected at one end thereof to ear 138 of member 94 by a pivot pin 154, and a similar and symmetrically disposed spring projected rod 156 is pivotally connected to ear 140 of member 96 by a pivot pin 158. The opposite ends of rods 152 and 156 are each slidable in a bracket 160 secured to casing wall 90. As rods 152 and 156 and the companion brackets 160 are of the same construction, and as the spring projected rods 152 and 156 are in symmetrical relation to member 92 in the neutral position of the operating mechanism, a description of the construction of operating rod 152 and the companion bracket 160 also applies to rod 156 and the companion bracket for the latter. Thus, as illustrated in Figs. 7 and 10, rod 152 comprises two longitudinally extending parts 162 and 164 welded to each other in face to face relation and having spaced end portions 166 and 168, respectively, whereby rod 152 is provided with a forked end 170 between which ear 138 of member 94 is received, said end portions 166 and 168 being provided with aligned apertures 172 for the pivot pin 154 which connects ear 138 to said rod. End portions 166 and 168 are enlarged to form a shoulder 174 which is engaged by one end of a coiled compression spring 176. The other end of said spring bears against the lateral portion 178 of bracket 160, said lateral portion being provided with a slot 180 through which rod 152 is slid able. The lateral portion 178 of bracket 160 is provided at its upper edge with a lip 182 to prevent accidental disengagement of rod 152 from the bracket. It will be understood that the spring 184 of spring projected rod 156 is associated with said rod and with the companion bracket in the same way as just described with reference to spring 178 of rod 152. Members 94 and 96 may be referred to as toggle members as they form toggles with the companion spring pressed rods 152 and 156, respectively.

In the neutral position of the mechanism illustrated in Fig. 7, the edges of parts 142 and 144 of members 94 and 96, respectively, engage the adjacent side edges of member 92, thus maintaining the latter in its central or neutral position by reason of the equal opposing action of springs 176 and 184.

The operation of the switch operating mechanism for engaging movable contact member 42 with and disengaging the same from the companion stationary contact member 26 or the companion stationary contact member 28 takes place initially in response to the movement of control member 106 and is completed by the over-centering of spring projected rods 152 or 156, there being a lost motion connection between control member 106 and members 94 and 96 by reason of the slots 132 and 136 having a circumferentially greater extent than the companion lugs 126 and 134 of members 94 and 96, respectively. Thus, assuming that the movable contact member 42 is in its neutral position, and the switch operating mechanism is in the position illustrated in Fig. 7, when it is desired to engage the movable contact member with the companion stationary contact member 26, control member 106 is moved up-

wardly (viewing Fig. 2) or in a counter-clockwise direction (viewing Fig. 7). When the control member is thus moved, lug 126 of member 94 is engaged by the right hand end of slot 132 (Fig. 2) and lug 116 is engaged by one radial edge of recess 118 so that members 94 and 92 are moved in unison in a counter-clockwise direction, viewing Fig. 7, with compression of spring 176 of rod 152, until the toggle constituted by said rod and the companion toggle member 94 is overcentered, at which time spring projected rod 176 moves member 96 and member 92 in the same direction independently of control member 106, which independent movement is permitted by the above mentioned lost motion connection between said control member and lug 126 of member 94. The position of the parts at the end of this movement of members 92 and 94 initiated by control member 106 and completed by spring projected rod 152 is illustrated in Fig. 8. During this movement lug 122 engages crank arm 66 of crank member 56 and thereby turns said crank member on its pivoted end portions 60 and 62 so that switch blade 48 is positively moved toward the companion stationary contact member 26 part of the total distance from the neutral position of the contact member 42 to the position in which blade 48 engages the companion stationary contact member 26 and thereafter, upon the overcentering of the toggle, said blade 48 of the movable contact member snaps into engagement with said companion stationary contact member 26, thus effecting a quick make with said contact member.

When it is desired to disengage the blade 48 of movable contact member 42 from said stationary contact member 26, control member 106 is moved in a clockwise direction, viewing Fig. 8, or in a counter-clockwise direction from the dotted line position of said handle illustrated in Fig. 2, whereby one edge of slot 132 engages lug 126 of member 94, thereby causing pivotal movement of member 94 and subsequently pivotal movement of member 92 by reason of the engagement of one radial edge of recess 118 of member 94 with lug 116 of member 92, in a clockwise direction, viewing Fig. 8. During this movement, lug 122 of member 92 engages crank arm 66 of crank member 56 and turns the latter on its aligned pivot portions 60 and 62, and also during this movement spring 176 is compressed until the toggle constituted by spring projected rod 152 and member 94 is overcentered, at which time spring projected rod 152 moves members 94 and 92 in the same direction independently of control member 106 thereby moving movable contact member 42 to the neutral position illustrated in Fig. 7. During this clockwise movement of control member 106 and the subsequent movement in the same direction of members 94 and 92 by spring projected rod 152, independently of the control member, in the same direction, the switch blade 48 is positively moved in a direction to disengage the companion stationary contact member 26, but does not disengage the latter until the toggle is overcentered, at which time contact blade 48 disengages the stationary contact member 26 with a snap action, thus effecting a quick break for opening of the switch and movement of the movable contact member 42 with a snap action to its neutral position.

The operation of the switch operating mechanism for engaging blade 50 of the movable contact member 42 with the companion stationary contact member 28 comprises moving the control member 106 in a clockwise direction, view-

ing Fig. 7, whereby member 96 and subsequently member 92 are rotated in said direction positively by the control member until the toggle constituted by spring projected rod 156 and member 96 is overcentered, whereupon the movable contact member is moved with a snap action so that contact blade 50 is brought into rapid engagement with the companion stationary contact member 28 independently of control member 106, the switch operating mechanism being in the position illustrated in Fig. 9. When it is desired to move the movable contact member from the position illustrated in Fig. 9, in which contact blade 50 is in engagement with the companion stationary contact member 28, to its neutral position, the control member is moved in a counter-clockwise direction, viewing Fig. 9, and the movable contact member is moved positively by the members 96 and 92 until the toggle constituted by spring projected rod 156 and member 96 is overcentered, after which the contact blade 50 is moved with a snap action out of engagement with the companion stationary contact member 28, independently of control member 106 to the neutral position of movable contact member 42, the position of the operating mechanism at that time being illustrated in Fig. 7.

It will be noted that the toggle including member 94 having its operation initiated by control member 106 and completed by spring projected rod 152 is effective to engage switch blade 48 with the companion stationary contact member 26 for effecting a quick make connection between the movable contact member and the companion stationary contact member 26, and that when the movable contact member is in engagement with the companion stationary contact member 28, a similar movement of control member 106 results in the operation of the toggle constituted by member 96 and rod 156 for effecting the disengagement of the movable contact member with a quick break from the companion stationary contact member 28 and the movement of said movable contact member to its neutral position. Likewise, it will be observed that when control member 106 is moved in a counter-clockwise direction, viewing Fig. 2, movement of the movable contact member out of engagement with the companion stationary contact member 26 to a neutral position is effected by operation of the toggle which includes member 94, this operation being initiated by said movement of control member 106 and completed by the overcentering of this toggle. Similarly, it will be observed that the engagement of movable contact member 42 with the companion stationary contact member 28 is accomplished by the operation of the toggle, which includes member 96, which is initiated by the movement of control member 106 in a counter-clockwise direction, viewing Fig. 2, and completed by the overcentering of the toggle.

Provision is made for releasably latching the operating mechanism in neutral position. For this purpose a detent member 186 is pivotally mounted at one end 188 thereof on casing wall 90 externally thereof adjacent to the hub portion 108 of control member 106. Said detent member 186 is provided with a detent element 190 which releasably engages hub portion 108 of control member 106 in a recess 192. It will be understood that when detent element 190 is in recess 192, control member 106 is locked in its neutral position against movement in either direction whereby to prevent closing of the switch. Detent member 186 is releasably held in locking

position by a spring 194 which is positioned on the inside of casing 12 adjacent wall 90 thereof (Fig. 7). One end of said spring is secured to a lug 196 on the inner surface of said casing wall 90 and the other end of said spring is fixed to a pin 198 which projects through an arcuate slot 200 in casing wall 90 and is secured to a laterally projecting portion 202 of detent member 186. Said detent member is also provided with a finger piece 204 for convenience in operating the same to release the control member 106. Provision is made for locking detent 186 in latching position, and for this purpose said detent is provided with an apertured ear 206 which is in alignment with an apertured lug 208 fixed to the front of casing wall 90 (Fig. 2). Any suitable lock may be utilized for securing apertured ear 206 to said lug 108 to prevent unauthorized release of detent member 186 from control member 106. The releasable latching device also comprises an operating member 210 (Figs. 2 and 7) which is positioned adjacent casing wall 90 on the inner side thereof and has an end portion 212 which projects outwardly of the casing through a slot 214 provided in the inturned edge 216 of said casing wall and through a slot in the cover 14 of the casing. The lower end of operating member 210 has a lateral extension 218 provided with a slot 220 in which pin 198 of detent member 186 is engaged. It will be understood that detent 186 can be moved to its retracted position out of engagement with control member 106 by moving the operating member 210 inwardly of the casing toward casing wall 22. Thus as illustrated in Fig. 7 operating member 210 is in its projected position in which it is releasably held by spring 194 which is connected to pin 198, detent member 186 being in latching engagement with control member 106, while in Figs. 7 and 9 operating member 210 is shown in its retracted position to which it was moved for releasing said detent member from control member 106. It will be understood that in order to actuate control member 106 for closing the switch, it is necessary to release detent member 186 from the control member 106. Also, it will be understood that when the control member 106 is operated for disengaging the movable contact member 42 from either of its companion stationary contact members 26 or 28, the detent member automatically engages the control member 106 as soon as the movable contact member reaches its neutral position, thus preventing a continuous movement of the switch operating member 106 so that unless the detent member is released from the operating member, the movable contact member can not be moved from one contact 26 to the other contact 28, that is from one side of the double-throw switch to the other side thereof. This is desirable especially when the double-throw switch is used as a motor-reversing switch. It will be understood, however, that while the control member latching device is desirable, it may be omitted. From the preceding description, it is apparent that the control member latching device is independent of and operates independently of the position of the casing cover 14, and it will be observed that said latching device is effective in the normal condition of the switch, i. e., when the casing cover is closed, to prevent a continuous movement of operating handle 106 and thereby to prevent an unintended movement of the movable contacts from one set of stationary contacts, through the neutral position, to the other set of stationary contacts, and it will

be noted also that said latching device is operative in the normal condition of the switch, when casing cover 14 is closed, to releasably prevent movement of the movable contact members from their neutral position.

While I have shown and described the preferred embodiment of my invention, it will be understood that the latter may be embodied otherwise than as herein shown or described and that in the illustrated embodiment certain changes in the details of construction and in the arrangement of parts may be made. Also it will be understood that the operating mechanism may be used for operating a switch of a different construction than that herein illustrated. Accordingly, I do not wish to be limited to the invention as herein specifically illustrated or described except to the extent which may be required by the scope of the appended claims.

Having thus described my invention, what I claim and desire to secure by Letters Patent is:

1. An operating mechanism for a double-throw switch having a neutral position, said mechanism comprising an operating member mounted for movement in opposite directions and connected to the movable contact member of the switch, an actuating member movable in opposite directions and having a lost motion connection with said operating member and engageable with opposite sides of the latter for moving the same in said opposite directions, respectively, means for moving said actuating member in one of said directions comprising a toggle member connected to said actuating member and a spring projected rod connected to said toggle member and forming a toggle therewith, means for moving said actuating member in the opposite direction comprising a second toggle member connected to said actuating member and a spring projected rod connected to said second toggle member and forming a second toggle therewith, and means for controlling the operation of said toggles comprising a member mounted for movement in opposite directions and having a lost motion connection with each of said toggle members whereby the operation of each of said toggles is initiated by said control member and is completed independently of said control member with a snap action upon overcentering of the toggle by said control member.

2. A switch operating mechanism for a double-throw switch comprising a movable contact member having a neutral position between the closed positions thereof, said mechanism comprising a crank member mounted for oscillation and operatively connected to said movable contact member for moving the same to and from each of said positions thereof, said crank member having aligned pivot portions and crank arms adjacent said pivot portions, respectively, an actuating member mounted for pivotal movement in opposite directions co-axially of said pivot portions and having circumferentially spaced parts engageable, with a lost motion connection, with one of said crank arms at opposite sides thereof, respectively, for turning said crank member in opposite directions, means for moving said actuating member in one of said directions comprising a toggle member connected to said actuating member and a spring projected rod connected to said toggle member and forming a toggle therewith, means for moving said actuating member in the opposite direction comprising a second toggle member connected to said actuating member and a spring projected rod connected to said second toggle member and forming a toggle therewith, means for moving said actuating member in the opposite direction comprising a second toggle member connected to said actuating member and a spring projected rod connected to said sec-

ond toggle member and forming a second toggle therewith, each of said toggle members being pivotally movable co-axially of said actuating member and having a lug spaced radially of the pivotal axis, and a control member mounted for oscillation co-axially of said pivot portions, said control member having two circumferentially spaced arcuate slots in which said lugs are, respectively, received, said slots having a greater circumferential extent than the companion lug therein, providing a lost motion connection of said control member with each of said toggle members whereby the operation of each of said toggles is initiated by said control member and is completed independently of said control member with a snap action upon overcentering of the toggle by said control member.

3. A switch operating mechanism for a double-throw switch having stationary contact members and a movable contact member engageable with and disengageable from said contact member, respectively, and movable to a neutral position, said mechanism comprising a crank member mounted for oscillation and operatively connected to said movable contact member for moving the same, said oscillatory crank member having aligned pivot portions, a crank portion between said pivot portions and crank arms connecting the opposite ends of said crank portion to said pivot portions, respectively, two members mounted for oscillation co-axially of said pivot portions, each of said last mentioned members having a lug and a radial ear spaced circumferentially of each other, a control member mounted for oscillation co-axially of said pivot portions, said control member having two circumferentially spaced arcuate slots in which said lugs are, respectively, received, said slots having a greater circumferential extent than the companion lug therein, an actuating member mounted for oscillation co-axially of said pivot portions and operatively connected to each of said two members for pivotal movement in one direction by one of said two members and for pivotal movement in an opposite direction by the other of said two members, and overcentering spring-projected rods connected to said two members, respectively, for moving the latter with a snap action independently of the control member after a predetermined movement of the latter.

4. A double-throw switch comprising a casing, stationary and movable contact members mounted in said casing, a crank member operatively connected to said movable contact member for actuating the same, said crank member having aligned pivot portions, means providing bearings for said pivot portions, respectively, one of said means comprising a mounting member having a part positioned within said casing and provided with a cylindrical recess in which one of said pivot portions is journaled for oscillation, a cylindrical stem in fixed relation to and projecting from said part co-axially with said recess, said casing having a wall provided with an opening through which said stem projects from within said casing, means mounted for oscillation on a part of said stem and relatively thereto within said casing adjacent said wall and operatively connected to said crank member for actuating the latter, and a control member mounted for pivotal movement on a part of said stem relatively thereto externally of said casing and operatively connected to said actuating means for operating the latter.

5. A double-throw switch comprising a cas-

ing, stationary and movable contact members mounted in said casing, a crank member operatively connected to said movable contact member for actuating the same, said crank member having aligned pivot portions, means providing bearings for said pivot portions, respectively, an actuating member mounted for oscillation on a part of said stem and engageable with said crank member for oscillating the same in two directions, a pair of toggle members mounted for oscillation on a part of said stem within said casing and operatively connected to said actuating member for turning the same in opposite directions, respectively, said casing wall having an arcuate slot concentric with said opening, each of said toggle members having a lug projecting through said arcuate slot to the outside of said casing wall, and a control member mounted on a part of said stem externally of said casing for oscillation co-axially with toggle members and provided with a pair of circumferentially spaced slots in which said lugs, respectively, engage said control member for operatively connecting the latter to said toggle members.

6. A double-throw switch comprising a casing, stationary and movable contact members mounted in said casing, a crank member operatively connected to said movable contact member for actuating the same, said crank member having aligned pivot portions, means providing bearings for said pivot portions, respectively, one of said means comprising a mounting member having a part positioned within said casing and provided with a cylindrical recess in which one of said pivot portions is journaled for oscillation, a cylindrical stem projecting from said part co-axially with said recess, said casing having a wall provided with an opening through which said stem projects from within said casing, means mounted for oscillation on a part of said stem within said casing adjacent said wall and operatively connected to said crank member for actuating the latter, and a control member mounted on a part of said stem externally of said casing and operatively connected to actuating means for operating the latter, an actuating member mounted within said casing for pivotal movement in two directions co-axially of said pivot portions and having a lost motion connection with said crank member for turning the same in either of two directions, a pair of toggle members mounted within said casing for turning movement co-axially with said pivot portions and operatively connected to said actuating member for turning the latter in opposite directions, respectively, said casing having a wall provided within an arcuate slot concentric with the pivotal axis of said pivot portions, each of said toggle members having a lug projecting through said arcuate slot and movable circumferentially thereof, a control member mounted for oscillation co-axially of said pivot portions, said control member having two circumferentially spaced arcuate slots in which said lugs are, respectively, received, said slots having a greater circumferential extent than the companion lug therein, providing a lost motion connection of said control member with each of said toggle members.

7. A double-throw switch comprising a casing, stationary and movable contact members mounted in said casing, a crank member operatively connected to said movable contact member for actuating the same, said crank member having aligned pivot portions, means providing bearings for said pivot portions, respectively, one of said means comprising a mounting member hav-

ing a part positioned within said casing and provided with a cylindrical recess in which one of said pivot portions is journaled for oscillation, a cylindrical stem projecting from said part co-axially with said recess, said casing having a wall provided with an opening through which said stem projects from within said casing, means mounted for oscillation on a part of said stem within said casing adjacent said wall and operatively connected to said crank member for actuating the latter, and a control member mounted on a part of said stem externally of said casing and operatively connected to actuating means for operating the latter, an actuating member mounted within said casing for pivotal movement in two directions co-axially of said pivot portions and having a lost motion connection with said crank member for turning the same in either of two directions, means for moving said actuating member in one of said directions comprising a toggle member connected to said actuating member and a spring projected rod connected to said toggle member and forming a toggle therewith, means for moving said actuating member in the opposite direction comprising a second toggle member connected to said actuating member and a spring projected rod connected to said second toggle member and forming a second toggle therewith, said casing having a wall provided within an arcuate slot concentric with the pivotal axis of said pivot portions, each of said toggle members having a lug projecting through said arcuate slot and movable circumferentially thereof, a control member mounted for oscillation co-axially of said pivot portions, said control member having two circumferentially spaced arcuate slots in which said lugs are, respectively, received, said slots having a greater circumferential extent than the companion lug therein, providing a lost motion connection of said control member with each of said toggle members.

8. A switch comprising a casing, stationary and movable contact members mounted in said casing, a crank member operatively connected to said movable contact member for actuating the same, said crank member having aligned pivot portions, means providing bearings for said pivot portions, respectively, one of said means comprising a mounting member having a part positioned within said casing and provided with a cylindrical recess in which one of said pivot portions is journaled for oscillation, a cylindrical stem projecting from said part co-axially with said recess, said part having a shoulder-forming portion extending radially outwardly of said stem, said casing having a wall provided with an opening through which said stem projects from within said casing, a plurality of members for actuating said crank member pivotally mounted on said stem between said shoulder-forming portion and the inner surface of said wall, and means holding said stem and said members mounted thereon against movement in a direction axially of said casing opening through which said stem projects.

9. An operating mechanism for a double-throw switch having a neutral position, said mechanism comprising an operating member mounted for movement in opposite directions and connected to the movable contact member of the switch, an actuating member movable in opposite directions and having a lost motion connection with said operating member and engageable with opposite sides of the latter for moving the same in said opposite directions, respectively, means for moving

said actuating member in one of said directions comprising a toggle member connected to said actuating member and a spring projected rod connected to said toggle member and forming a toggle therewith, means for moving said actuating member in the opposite direction comprising a second toggle member connected to said actuating member and a spring projected rod connected to said second toggle member and forming a second toggle therewith, said toggle members being mounted for co-axial pivotal movement independently of each other, and a control member mounted for pivotal movement co-axially with said toggle members, each of said toggle members having a lug spaced radially from the pivotal axis of said members, said control member having a pair of arcuate slots concentric with said pivotal axis, said lugs projecting into said slots, respectively, and engageable by said control member for turning said toggle members in opposite directions, respectively.

10. An operating mechanism for a double-throw switch having a neutral position, said mechanism comprising an operating member mounted for movement in opposite directions and connected to the movable contact member of the switch, an actuating member movable in opposite directions and having a lost motion connection with said operating member and engageable with opposite sides of the latter for moving the same in said opposite directions, respectively, means for moving said actuating member in one of said directions comprising a toggle member connected to said actuating member and a spring projected rod connected to said toggle member and forming a toggle therewith, means for moving said actuating member in the opposite direction comprising a second toggle member connected to said actuating member and a spring projected rod connected to said second toggle member and forming a second toggle therewith, said toggle members being mounted for co-axial pivotal movement independently of each other, and a control member mounted for pivotal movement co-axially with said toggle members, each of said toggle members having a lug spaced radially from the pivotal axis of said members, said control member having a pair of arcuate slots concentric with said pivotal axis, said lugs projecting into said slots, respectively, and engageable by said control member for turning said toggle members in opposite directions, respectively.

11. In a double-throw switch comprising a pair of stationary contact members and a movable contact member mounted for pivotal movement from a neutral position to positions in engagement with said stationary contact members, respectively, at opposite sides of the pivotal axis of said movable contact member, a crank member for operating said movable contact member having aligned pivot portions, by which said crank member is mounted for turning movement, and an offset crank portion between said pivot portions, said crank portion extending parallel to the pivotal axis of said movable contact member, a connection between said movable contact member and said crank portion comprising means rigidly secured to said movable contact member and secured to said crank portion in relative rotary re-

lation thereto, means mounted for movement co-axially of said pivot portions and operatively connected to said crank member for turning the latter, and movable means releasably engageable with a part of said last means in the normal condition of the switch for releasably preventing movement of said movable contact member from moving from said neutral position.

12. In a double-throw switch comprising a pair of stationary contact members and a movable contact member mounted for pivotal movement from a neutral position to positions in engagement with said stationary contact members, respectively, at opposite sides of the pivotal axis of said movable contact member, a crank member for operating said movable contact member having aligned pivot portions, by which said crank member is mounted for turning movement, and an offset crank portion between said pivot portions, said crank portion extending parallel to the pivotal axis of said movable contact member, said movable contact member comprising two contact portions in angular relation, one of said contact portions being engageable with one of said stationary contact members and the other of said contact portions being engageable with the other of said stationary contact members, a connection between said movable contact member and said crank member comprising means secured to said contact portions and engaging said crank portion in relative rotary relation thereto, means mounted for movement co-axially of said pivot portions and operatively connected to said crank member for turning the latter, and movable means releasably engageable with a part of said last means in the normal condition of the switch for releasably preventing movement of said movable contact member from moving from said neutral position.

13. In a double-throw switch comprising a pair of stationary contact members and a movable contact member mounted for pivotal movement from a neutral position to positions in engagement with said stationary contact members, respectively, at opposite sides of the pivotal axis of said movable contact member, a crank member for operating said movable contact member having aligned pivot portions, by which said crank member is mounted for turning movement, and an offset crank portion between said pivot portions, said crank portion extending parallel to the pivotal axis of said movable contact member, said movable contact member comprising two contact portions in angular relation, one of said contact portions being engageable with one of said stationary contact members and the other of said contact portions being engageable with the other of said stationary contact members, a connection between said movable contact member and said crank member, means mounted for pivotal movement co-axially of said pivot portions and operatively connected to said crank member for turning the latter, and movable means releasably engageable with a part of said last mentioned means in the normal condition of the switch for preventing a continuous movement of said movable contact member from either of said stationary contact members to the other stationary contact member.

14. In a double-throw switch comprising a pair of stationary contact members and a movable contact member mounted for pivotal movement from a neutral position to positions in engagement with said stationary contact members, respectively, at opposite sides of the pivotal axis of

said movable contact member, means for actuating said movable contact member to engage and disengage either of said stationary contact members, a casing for said switch having a cover movable to open and closed positions, and means movably mounted on said casing and releasably engageable with a part of said last mentioned means for releasably preventing a continuous movement of said movable contact member from either of said stationary contact members to the other stationary contact member when said casing cover is in said closed position thereof.

15. In a double-throw switch comprising a pair of stationary contact members and a movable contact member mounted for pivotal movement from a neutral position to positions in engagement with said stationary contact members, respectively, at opposite sides of the pivotal axis of said movable contact member, means for actuating said movable contact member to engage and disengage either of said stationary contact members, a casing for said switch having a cover movable to open and closed positions, and means movably mounted on said casing and releasably engageable with a part of said actuating means when said cover is in said closed position thereof for releasably preventing operation of said actuating means when said movable contact member is in said neutral position thereof.

16. A double-throw switch comprising a casing, stationary and movable contact members mounted in said casing, a crank member operatively connected to said movable contact member for actuating the same, said crank member having aligned pivot portions, means providing bearings for said pivot portions, respectively, one of said means comprising a mounting member having a part positioned within said casing and provided with a cylindrical recess in which one of said pivot portions is journaled for oscillation, a cylindrical stem projecting from said part co-axially with said recess, said casing having a wall provided with an opening through which said stem projects from within said casing, means mounted for oscillation on a part of said stem within said casing adjacent said wall and operatively connected to said crank member for actuating the latter, a control member mounted on a part of said stem externally of said casing and operatively connected to actuating means for operating the latter, and means movably mounted on said casing and releasably engageable with said control member in the normal condition of the switch for holding the latter releasably in neutral position, said control member having a recess, said last mentioned means comprising a member pivotally mounted on said casing and having a projection movable into said recess, and spring means biasing said member to a position in which said projection is engaged in said recess.

17. An operating mechanism for a double-throw switch having a neutral position, said mechanism comprising an operating member mounted for movement in opposite directions and connected to the movable contact member of the switch, an actuating member movable in opposite directions and having a lost motion connection with said operating member and engageable with opposite sides of the latter for moving the same in said opposite directions, respectively, means for moving said actuating member in one of said directions comprising a toggle member connected to said actuating member and a spring projected rod connected to said toggle member and forming a toggle therewith, means for moving said actuating

member in the opposite direction comprising a second toggle member connected to said actuating member and a spring projected rod connected to said second toggle member and forming a second toggle therewith, said actuating member having a lost motion connection with each of said toggle members, and means for controlling the operation of said toggles comprising a member mounted for movement in opposite directions and having a lost motion connection with each of said toggle members whereby the operation of each of said toggles is initiated by said control member and is completed independently of said control member with a snap action upon overcentering of the toggle by said control member.

18. A switch operating mechanism for a double-throw switch having stationary contact members and a movable contact member engageable with and disengageable from said contact member, respectively, and movable to a neutral position, said mechanism comprising a crank member mounted for oscillation and operatively connected to said movable contact member for moving the same, said oscillatory crank member having aligned pivot portions, a crank portion between said pivot portions and crank arms connecting the opposite ends of said crank portion to said pivot portions, respectively, two members mounted for oscillation co-axially of said pivot portions, each of said last mentioned members having a lug and a radial ear spaced circumferentially of each other, a control member mounted for oscillation co-axially of said pivot portions, said control member having two circumferentially spaced arcuate slots in which said lugs are, respectively, received, said slots having a greater circumferential extent than the companion lug therein, an actuating member mounted for oscillation co-axially of said pivot portions and operatively connected to each of said two members for pivotal movement in one direction by one of said two members and for pivotal movement in an opposite direction by the other of said two members, said two members each having an arcuately extending recess therein and said actuating member having an axially extending lug projecting into said recesses, the circumferential extent of said last mentioned lug being less than the circumferential extent of each of said recesses whereby to provide a lost motion connection between said actuating member and each of said two members, and overcentering spring-projected rods connected to said two members, respectively, for moving the latter with a snap action independently of the control member after a predetermined movement of the latter.

19. An operating mechanism for a double-throw switch having a neutral position, said

mechanism comprising an operating member mounted for movement in opposite directions and connected to the movable contact member of the switch, an actuating member movable in opposite directions and having a lost motion connection with said operating member and engageable with opposite sides of the latter for moving the same in said opposite directions, respectively, means for moving said actuating member in one of said directions comprising a toggle member connected to said actuating member and a spring projected rod connected to said toggle member and forming a toggle therewith, means for moving said actuating member in the opposite direction comprising a second toggle member connected to said actuating member and a spring projected rod connected to said second toggle member and forming a second toggle therewith, and means for controlling the operation of said toggles comprising a member mounted for movement in opposite directions and having a lost motion connection with each of said toggle members whereby the operation of each of said toggles is initiated by said control member and is completed independently of said control member with a snap action upon overcentering of the toggle by said control member, a casing for said switch, and means operative in the normal condition of the switch for releasably holding said control member in a neutral position and for releasably preventing movement of said control member through said neutral position thereof from a different position thereof, said last mentioned means comprising means movably mounted on said casing and releasably interlocked with said control member.

20. In a double-throw switch comprising a pair of stationary contact members and a movable contact member mounted for pivotal movement from a neutral position to positions in engagement with said stationary contact members, respectively, at opposite sides of the pivotal axis of said movable contact member, means for actuating said movable contact member to engage and disengage either of said stationary contact members, a casing for said switch having a cover movable to open and closed positions, and means movably mounted on said casing and releasably engageable with a part of said actuating means, when said cover is in said closed position thereof, for releasably preventing operation of said actuating means when said movable contact member is in said neutral position thereof, and means accessible externally of the switch casing for positively disengaging said movable means from said part of the actuating means.

THOMAS M. COLE.
